Primary Examiner — Messina L Smith*Assistant Examiner* — Jennifer B Salazar(74) *Attorney, Agent, or Firm* — Nitin Kaushik(57) **CLAIM**

The ornamental design for a pet bed, as shown and described.

DESCRIPTION

FIG. 1 is a front perspective view of a pet bed, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion of the pet bed shown in area 9 in FIG. 1; and,

FIG. 10 is an enlarged view of a portion of the pet bed shown in area 10 in FIG. 2.

The broken lines representing stitching are part of the claimed design.

The dash-dot-dash broken lines encircling the enlarged views are for annotative purposes only and form no part of the claim thereof.

1 Claim, 10 Drawing Sheets(56)
